APPARATUS FOR HEAT TREATING
MATERIALS

Reed W. Hyde, Summit, N. J.

Application March 25, 1931. Serial No. 525,161

7 Claims. (Cl. 18—1)

This invention relates to an apparatus for heat treating material and more particularly to an apparatus for successively treating said material in layers to produce a light weight cellular product.

The invention provides for completely heat treating each layer before the next successive layer is applied thereto to form a cellular cake which is substantially homogeneous and in which the various layers are joined together as an integral unit. The heat treatment may be accomplished by applying hot gases to the various layers, or by drawing the gases through said layers as they are successively applied in a heat treating apparatus.

The invention may be applied particularly to the burning of materials, such as clay, to form a concrete aggregate material. It may also be applied to other materials which have a relatively extended softening range, rather than a sharp melting point, such as, shales, argillites and similar rocks.

The invention also consists in certain new and original features of construction and combinations of parts hereinafter set forth and claimed.

Although the novel features which are believed to be characteristic of this invention will be particularly pointed out in the claims appended hereto, the invention itself, as to its objects and advantages, and the manner in which it may be carried out, may be better understood by referring to the following description taken in connection with the accompanying drawings forming a part thereof, in which

Fig. 1 is a side elevation of an apparatus constructed in accordance with the present invention;

Fig. 2 is a section taken on the line 2—2 of Fig. 1;

Fig. 3 is a side elevation of a modified form of apparatus; and

Fig. 4 is a section taken on the line 4—4 of Fig. 3.

Like reference characters denote like parts in the several figures of the drawings.

In the following description and in the claims, various details will be identified by specific names for convenience, but they are intended to be as generic in their application as the art will permit.

Referring to the drawings the apparatus is shown as comprising a framework 10 of structural steel or other suitable supporting material carrying an endless track 11 on which a plurality of pallets 12, having perforate bottoms or

grates 13, are supported. Said pallets are propelled along track 11 by suitable means, such as driving wheel 14, which is actuated from a motor 15 through intermediate gears 16. A wind box 20 is supported on framework 10 beneath pallets 12 in such position that the pallets 12 pass over said wind box as they are progressively moved along track 11. The top of said wind box is adapted to make a close seal with the bottoms of said pallets whereby leakage of gases is reduced to a minimum. Said wind box may be connected by a pipe 22 to a suitable source of suction (not shown) and may be provided with hinged doors 21 which afford access to the interior for cleaning purposes.

A heating chamber 25 is also supported by said frame 10 and is positioned above said pallets and in communication therewith. Said chamber comprises roof 26, side walls 27 and bottom members 28, the latter projecting slightly over the side walls of the pallets to protect them from the intense heat within the chamber and to effect a relatively close joint whereby leakage of gases is prevented. Flexible members 29 of heat resisting material may be secured to the members 28 and engage the sides of pallets 12 for effecting a further seal. A plurality of ports 30 are formed in the side walls 27 and communicate with fuel burners 31 by which highly heated gases are admitted to the heating chamber. These ports are so located that the gases entering therethrough make contact with and cover substantially the entire surface of the material being transported through the heating chamber by the pallets. It is obvious that the ports may be variously located, as for example, in the side walls, roof, bottom members or the end walls of the chamber, depending upon the particular fuel employed and the size of the chamber. Furthermore, they are so arranged as to number and position that the heat in the various parts of the chamber may be controlled and preferably so that uniform heat may be maintained in the entire chamber.

In the form of the invention illustrated, the side walls are spaced back from the edges of the pallets to provide a combustion chamber extending the length of the heating chamber on either side thereof. In this combustion chamber the fuel-air mixture which is received through ports 30 may be completely burned before the hot gases contact with the material undergoing treatment. This is particularly advantageous where a type of burner is employed which normally throws a long flame. In certain instances this combustion chamber may be omitted, provided sufficient com-

bustion space is present so that the gases are completely burned and raised to a high temperature before they are applied to the surface of the material. The spent gases which have been drawn through the material and which may still retain considerable heat may be utilized in any convenient manner for the recovery of the waste heat therefrom.

At intervals along the roof and positioned transversely thereof, are a plurality of apertures 35 through which the material is admitted in a manner to be pointed out. These apertures are preferably spaced uniformly and the first and last apertures are preferably located a substantial distance from the end walls of the heating chamber. The apertures are of such length that the material dropped through them is uniformly spread across the entire pallet.

A plurality of storage hoppers 36 are mounted above said apertures and are associated with a discharge mechanism, such as rotating drums 37, which receive material from said hoppers and apply the same through said apertures. A suitable control valve 38 may be associated with each hopper for controlling the rate of discharge of material therefrom and a shield 39 may be associated with each of said discharge mechanisms to prevent escape of hot gases.

Cylinders 37 may be rotated by any convenient drive, as by gears 40, mounted on shaft 41, and driven by belt 42 which cooperates with one of said gears 16.

The preliminary feed hopper 45 is also supported on frame 10 and is located in front of heating chamber 25 in a position to apply the first layer of material to the pallets as they are passed thereunder. This hopper may also be provided with an adjustable outlet, but does not require a feeding device since the conveyor elements passing beneath it carry out a layer of charge of the desired depth.

In the operation of this form of the invention which may, for example, be applied to the burning of clay, the clay or other material to be treated is supplied to each of the hoppers 36 and 45. As the pallets pass under hopper 45 they receive a thin bed of charge which may, for example, be one-half inch in thickness, this being regulated by adjustment of the discharge mechanism. This charge is carried into the heating chamber and is heated by the hot gases therein. Said gases are received from burners 31 and ports 30, spread over the entire surface of the charge and are drawn downwardly through the charge into wind box 20. The speed of travel of the pallets, the heat of the gases and the thickness of the layer are regulated so that the layer is completely burned and its heat treatment finished by the time it arrives beneath the first aperture 35.

When the layer passes beneath said first aperture an additional layer of material is deposited thereon from the cooperating hopper 36 and the discharge mechanism 37. This layer cools the lower layer by absorption of heat and it itself treated in a manner similar to the first layer as it is conveyed forward in the heating chamber. The apparatus is so adjusted that the second layer is completely treated by the time the second aperture 35 is reached, whereupon a third layer will be deposited thereon and the treatment repeated.

After the final layer has been deposited and heat treated, the pallets move out of the heating chamber and discharge their load as they pass around the curved portion of the track.

It will be understood that the burners may be

regulated to provide the proper temperature within the heating chamber, and the rate of travel of the conveyor likewise may be regulated as by control at the motor, and that various temperatures, rates of travel and thicknesses of layer will be suitable for various materials.

For example, when treating clay which has been crushed to pass half inch screen, it was found that with a temperature in the heating chamber of approximately 1800° F. a half inch layer of charge was burned in approximately three minutes, and the conveyor speed was correspondingly adjusted to give this time interval to each half inch layer. The finished product was discharged as a homogeneous cake with no indication of cleavage or separation between the layers, showing the uniformity and completeness of the heat treatment.

Referring to the form of the invention disclosed in Figs. 3 and 4 the apparatus is in general similar to that described in connection with Figs. 1 and 2 and the corresponding parts have been given similar reference numerals. In this form of apparatus, however, an endless pan conveyor 50 is employed which is passed around sprocket wheels 51 and driven in any convenient manner. Said pan conveyor is provided with an imperforate bottom and closely engages the bottom walls 28 of the heating chamber 25. In this form of the invention the hot gases are applied through suitable ports in roof 26 and are caused to impinge downwardly in the layer of material in pans 50. The gases, however, are not passed through the layer of material but are withdrawn through a stack 52 and discharged in any convenient manner. The hoppers are arranged as described in connection with Figs. 1 and 2 and successively apply layers of material to the pans as they pass thereunder. Each of said layers is heat treated before the next layer is added to the charge and the treatment is otherwise similar to that above described. With apparatus of this type, however, it may be preferable to employ somewhat thinner layers of charge than when the gases are drawn down through the layer as in Figs. 1 and 2.

It will be noted that an efficient, economical apparatus is provided for heat treating the material in superimposed layers, which may be readily controlled by suitable regulation of the temperature, time, thickness of layer and speed of operation so that the process becomes substantially automatic and continuous and requires but little labor or attention.

While certain novel features of the invention have been disclosed and are pointed out in the annexed claims, it will be understood that various omissions, substitutions and changes may be made by those skilled in the art without departing from the spirit of the invention.

What is claimed is:

1. In a heat treating apparatus, a heating chamber, a movable support for passing a layer of material through said chamber, a plurality of feeding means spaced along the roof of said chamber and adapted to apply successive layers of material to said support, said feeding means comprising hoppers and discharge mechanism associated with each hopper and adapted to apply predetermined quantities of material to said support, and means for supplying a hot gaseous medium over the entire surface of said material within said chamber.

2. An apparatus for heat treating materials comprising a heating chamber and a movable conveyor adapted to pass therethrough, said

- chamber having a plurality of transverse apertures spaced longitudinally thereof and extending across said conveyor, feeding means for feeding material through said apertures and causing said material to spread in uniform layers on said conveyor, and means for supplying a hot gaseous medium over the entire surface of said material within said chamber. 80
5. An apparatus for heat treating materials comprising a heating chamber and a movable conveyor adapted to pass therethrough, said chamber having a plurality of transverse apertures spaced longitudinally thereof and extending across said conveyor, means for continuously feeding material through each of said apertures and causing said material to form uniform layers on said conveyor, and means for supplying a hot gaseous medium over the entire surface of said material within said chamber. 85
10. An apparatus for heat treating materials comprising a heating chamber and a movable conveyor adapted to pass therethrough, said chamber having a plurality of transverse apertures spaced longitudinally thereof and means for continuously feeding material through each of said apertures and causing said material to form uniform layers on said conveyor, means for supplying a hot gaseous medium over the entire surface of said material within said chamber. 90
15. An apparatus for heat treating materials comprising a heating chamber and a movable conveyor adapted to pass therethrough, said chamber having a plurality of transverse apertures spaced longitudinally thereof and means for continuously feeding material through each of said apertures and causing said material to form uniform layers on said conveyor, and means for supplying a hot gaseous medium over the entire surface of said material within said chamber. 95
20. An apparatus for heat treating materials comprising a heating chamber and a movable conveyor adapted to pass therethrough, said chamber having a plurality of transverse apertures spaced longitudinally thereof and means for continuously feeding material through each of said apertures and causing said material to form uniform layers on said conveyor, means for supplying a hot gaseous medium over the entire surface of said material within said chamber. 100
25. An apparatus for heat treating materials comprising a heating chamber and a movable conveyor adapted to pass therethrough, said chamber having a plurality of transverse apertures spaced longitudinally thereof and means for continuously feeding material through each of said apertures and causing said material to form uniform layers on said conveyor, means for supplying a hot gaseous medium over the entire surface of said material within said chamber. 105
30. An apparatus for heat treating materials comprising a heating chamber and a movable conveyor adapted to pass therethrough, said chamber having a plurality of transverse apertures spaced longitudinally thereof and means for continuously feeding material through each of said apertures and causing said material to form uniform layers on said conveyor, means for supplying a hot gaseous medium over the entire surface of said material within said chamber. 110
35. An apparatus for heat treating materials comprising a heating chamber, a movable support for passing a layer of material through said chamber, said chamber having a roof provided with a plurality of transverse openings through which successive layers of charge may be applied to said support, feeding means associated with each of said transverse openings, discharge mechanism associated with each of said feeding means and adapted to remove material therefrom at a predetermined rate and to apply said material in a uniform manner through said openings, said discharge mechanism comprising a continuously rotating member adapted to pick up particles of charge from said feeding means and drop the same through said openings, and means for supplying a hot gaseous medium over the entire surface of said material within said chamber. 115
